UNITED STATES PATENT OFFICE.

ROBERT LINCOLN POLLOCK, OF STERLING, KANSAS.

HOT-AIR FURNACE.

1,241,274.

Specification of Letters Patent. Patented Sept. 25, 1917.

Application filed March 31, 1917. Serial No. 158,834.

To all whom it may concern:

Be it known that I, ROBERT L. POLLOCK, a citizen of the United States, and a resident of Sterling, in the county of Rice and State 5 of Kansas, have invented a new and Improved Hot-Air Furnace, of which the following is a full, clear, and exact description.

My invention relates to hot-air heating furnaces and has for its prime object to utilize to the fullest extent the maximum interior surface of the furnace for heating the air. The stated object is attained by constructing the furnace with inner and outer walls, thereby forming an air space within 10 the furnace at all sides thereof, and providing means affording passages through which the air is caused to pass and subjected to the heat of the fire box, the passages including air pipes associated with the grate, air pipes 15 in the fire box, near the top, and air boxes transverse to the upper air pipes above the same, the arrangement being such as to cause the air to pass through the furnace directly at the grate and above the same to 20 be effectively subjected to the heat thereof. The structure includes also an indirect smoke passage arranged so that the heat of the smoke may be availed of for heating the air in the furnace; as well as vertical air 25 shafts rising in the furnace from the air pit to the top.

Other objects of the invention and the advantages of the novel features characterizing the illustrated practical embodiment of 30 the invention will appear as the description proceeds.

Reference is to be had to the accompanying drawings forming a part of this specification in which similar reference characters 35 indicate corresponding parts in all the views.

Figure 1 is a longitudinal vertical section on the line 1—1, Fig. 4;

Fig. 2 is a front view of the furnace;

Fig. 3 is a transverse section on the line 45 3—3, Fig. 1;

Fig. 4 is a horizontal section on the line 4—4, Fig. 1;

Fig. 5 is a longitudinal vertical section on the line 5—5, Fig. 4;

Fig. 6 is a horizontal section on the line 6—6, Fig. 1;

Fig. 7 is a horizontal section on the line 7—7, Fig. 1.

My improved furnace is constructed with 55 an outer wall 10 and an inner structure or furnace proper 11 between the walls of which and outer wall 10, an air space is produced at all sides of the furnace. Back walls 12, 13 are provided in the furnace at 60 the back of the ash pit 14 and fire box 16, the wall 12 terminating at about the level of the grate and being joined at its top with the rear wall 13 and forming an air space between said walls 12 and 13. The numeral 65 15 indicates the ash box door and 17, the fire door, the openings closed by the respective doors leading to the ash box and fire box through tubular structure 18, 19, as best seen in Fig. 1. Any approved means may 70 be provided for supplying air to the interior of the furnace to be heated, a cold air pit being indicated in Figs. 2 and 3 by dotted lines and designated by the numeral 20. The top 21 of the furnace proper or inner structure 75 is spaced from the top 22 of the outer wall structure 10 and the said top 22 is provided with any suitable number of air outlets 23 which in practice will deliver the heated air to any approved system of distributing 80 pipes (not shown). On the inner top 21 a water pan 24 is provided to which an inlet pipe 25 leads, said pipe having a funnel 26.

Leading from the fire box 16 is a smoke outlet 27 which communicates with a U- 85 shaped smoke passage 28 extending to the bottom of the furnace, then upwardly and communicating by a smoke outlet 29 with the flue or chimney 30. In the top of the smoke passage 27 is an opening 31 leading 90 to the direct smoke passage 32 which communicates also with the chimney 30, the said hole 31 being controlled by a damper 33, the rod 34 of which extends to the outside of the furnace and is provided with a suitable handle 35. The arrangement is such that with the damper 33 raised, the smoke will tend to pass directly through the passage 32 to the chimney, whereas with the said damper closed the smoke will pass indirectly to the 100 chimney through the smoke passage 28.

In order to utilize the heat from the smoke passing through the passage 28, said passage is made to form an air chamber 36, the upper end of which opens into the space between the tops 21, 22. It will be observed from Figs. 4 and 7 that the passage 28 and chamber 36 extend the full width of the in- 105

ner structure 11, so that a large heating surface is thus produced to heat the air in the chamber 36. On the walls of smoke passage 28 radiating knobs 28^a may be employed.

5 At each side of the air chamber 36 in the space between the inner and outer side walls of the furnace, are vertical air shafts 37, the lower ends of said air shafts having air inlets 38, the inner sides of said air shafts being open to chamber 36, and the upper ends of said air passages being open to the air space at the top of the furnace. The numeral 39, Figs. 1 and 5, indicates transverse clean-out openings extending through the 10 air shafts 37 at the lower ends thereof to the bend of the smoke passage 28, said clean-out openings being accessible through doors indicated at 39^a, formed in the side walls 10, 11 as indicated in Figs. 1, 5, 6 and 7. In 15 addition to the vertical air shafts 37, air passes upwardly from the air pit 20 to the chamber or space 40 in the rear of the wall 13, said space extending at the top thereof at both sides of the smoke passage 27.

20 25 In order to effectively utilize the heat of the fire box, I provide air pipes 41 associated with and forming part of the grate, the said pipes alternating with grate bars 42 adapted to be operated as hereinafter described. The inner ends 43 of the pipes 41 extend into the air space between the walls 12 and 13 and advantageously are downturned, while the front ends 44 are upturned in the space between the inner and outer 30 front walls. In the upper portion of the fire box additional transverse air pipes 45 extend, the inner ends 46 being downturned in the air space 40 in the rear of the wall 13, while the forward ends 47 are upturned and 35 positioned in the space between the inner and outer front walls. It will thus be seen that the air pipes 41 are subjected to the heat at the grate while the upper pipes 48 are subjected to the heat in the upper portion of the fire box and air will thus be 40 caused to rise in the ends 44, 47, the air being drawn in through the rear ends of the pipes.

45 Above the pipes 45 and at right angles thereto I provide in the top of the fire box transverse air boxes 48 and as will be understood from Figs. 3 and 4, the said boxes 48 have air inlets 49 at one end at the under side and air outlets 50 at the opposite ends 50 at the top. The inlets and outlets of alternate air boxes 48 are reversed so that air passes oppositely in alternate boxes from one side of the furnace to the other, thereby causing air to pass from each side to the 55 opposite side in certain of the boxes, while the position of the said air boxes in the top of the fire box will cause an effective circulation of the air in an obvious manner.

60 In order to rock the grate bars 42 they are 65 formed rigid with a transverse centrally dis-

posed rocker bar 51 which is seated in bearings 52 in the opposite sides of the fire box. The rocker bar 51 is formed with an arm 53 from which an operating rod 54 extends through the front wall of the furnace to the exterior and is provided with a suitable head or handle 55.

70 It will be readily understood that the heat of the fire box is effectively utilized by highly heating the air and much of the heat 75 may be taken from the smoke by causing it to pass through the passage 28.

I wish to state in conclusion that although the illustrated example constitutes a practical embodiment of my invention, I do not 80 limit myself strictly to the mechanical details herein illustrated, since manifestly the same can be considerably varied without departure from the spirit of the invention as defined in the appended claims.

85 Having thus described my invention, I claim as new, and desire to secure by Letters Patent:

1. A hot-air furnace having inner and outer walls forming an air space therebetween, there being a communicating air space at the top of the furnace, a fire box, a smoke flue, a U-shaped smoke passage communicating with the fire box and with the smoke flue and having the bend thereof near 90 the bottom of the furnace in the rear of the fire box, a vertical air chamber, said U-shaped smoke passage extending at the front and back of and beneath the said vertical chamber, the said vertical air chamber 100 and U-shaped smoke passage extending approximately from one inner side wall to the other, and vertical air shafts between the inner and outer side walls adjacent to the ends of the said vertical air chamber, said 105 air shafts having air inlets at their lower ends and communicating at the sides with the said vertical air chamber and at the upper ends with the air space at the top of the furnace.

110 2. A hot-air furnace comprising inner and outer walls forming an air space around the furnace at all sides, a fire box in the furnace near the front within the inner walls, a smoke flue at the back of the furnace, a U-shaped smoke passage communicating with the fire box and with said smoke flue, a vertical air chamber at the front and back of and beneath which the said smoke passage extends, vertical air shafts between the inner and outer walls at the sides of the said vertical air chamber and communicating therewith, and a vertical air chamber between the back of the fire box and the front portion of the said U-shaped smoke passage. 120

3. A hot-air furnace having an outer wall, an inner structure within the outer wall and forming an air space within the latter, said inner structure including a fire box, air pipes disposed in the fire box and extend- 125 130

ing through opposite walls thereof, the respective ends of the air pipes forming air inlets and outlets communicating with the air space of the furnace, and air boxes disposed in the fire box above and at right angles to the said air pipes, said air boxes extending through opposite walls of the fire

box one end of each air box being open at the under side for the inlet of air and the opposite end being open at the upper side for the outlet of air, the inlets and outlets of alternate air boxes being reversely disposed.

ROBERT LINCOLN POLLOCK
